UNITED STATES PATENT OFFICE.

HERBERT H. STEELE, OF MARCELLUS, NEW YORK, ASSIGNOR TO THE MONARCH TYPE-WRITER COMPANY, OF SYRACUSE, NEW YORK, A CORPORATION OF NEW YORK.

TYPE-WRITING MACHINE.

No. 880,591.

Specification of Letters Patent.

Patented March 3, 1908.

Application filed December 16, 1907. Serial No. 406,683.

To all whom it may concern:

Be it known that I, HERBERT H. STEELE, citizen of the United States, and resident of Marcellus, in the county of Onondaga and State of New York, have invented certain new and useful Improvements in Type-Writing Machines, of which the following is a specification.

In its present form my invention relates to ribbon mechanism for typewriting machines.

Generally stated, the object of the invention is to provide means for changing or shifting automatically at a predetermined point or points in a line of writing from one character to another of printing or from one character to another of inking where there is provided a printing means or an inking means having a plurality of characteristics.

More specifically, in the present instance the automatic change or shift is from one field to another of a ribbon having a plurality of fields of different characteristics.

To the above and other ends the invention consists in the features of construction, combinations of devices and arrangements of parts hereinafter described and particularly pointed out in the claims.

As herein shown the invention is applied to a No. 3 Monarch front-strike typewriting machine, which machine employs a vibratory ribbon carrier normally maintaining the ribbon away from the printing point; but it is to be understood that the invention is applicable to other forms of writing machines and may be applied to machines which do not employ a vibratory ribbon carrier as well as to machines which do.

In carrying out the invention in the present instance two or more co-operating shifting members are provided, one or more on the traveling element or carriage of the machine and one on a fixed part of said machine, said shifting members being relatively adjustable to co-act at varying points in the carriage travel to bring about an alteration in the throw of the vibratory ribbon carrier, whereby the working or operative field of the ribbon, or that field which is presented to the action of the types, may be changed automatically at one or another of a plurality of predetermined points in the line of writing.

As the invention is shown carried out in the present instance it is to be noted that when the automatically operating shifting devices operate during the actuation of the

tabulating devices or printing keys, the ribbon is not bodily or physically shifted simultaneously thereby to change from one ribbon field to another, but that by said shifting operation provision is made for a different throw of the ribbon when subsequently a printing key is struck. Thus in substance and effect the ribbon is shifted or changed by said shifting devices to cause a change of field, this change or shift from one ribbon field to another taking place automatically during the operation of the machine. Generic claims to this invention will be found in my application Serial No. 332,949 filed September 1st, 1906, the claims herein being directed to subject-matter not found in said application nor in my companion applications Serial Nos. 332,950 and 332,951, both filed September 1st, 1906.

In the accompanying drawings, Figure 1 is a longitudinal vertical sectional view of a typewriting machine embodying the invention, parts of the machine being omitted and parts broken away. Fig. 2 is a horizontal sectional view taken on a plane beneath the top plate, the top plate being shown by dotted lines and various parts of the machine being omitted and broken away. Fig. 3 is a fragmentary front elevation partly in section of the upper right-hand corner portion of the machine. Fig. 4 is a fragmentary rear elevation of the upper part of the machine, parts being omitted and parts broken away. Fig. 5 is a sectional rear elevation showing various parts illustrated in Fig. 4, some of said parts being in different relations from those in which they appear in said Fig. 4, various other parts shown in the latter figure being omitted. Fig. 6 is a view corresponding to Fig. 5 but showing various parts in different relations from those in which they appear in Figs. 4 and 5, various other parts shown in these latter figures being omitted. Fig. 7 is a view corresponding to Fig. 5 but showing various parts in different relations from those in which they appear in Figs. 4, 5 and 6, various other parts being omitted. Fig. 8 is a side sectional elevation showing the manual devices for effecting change of ribbon fields.

Referring more especially to Fig. 1, the main frame of the machine comprises a base 1, corner posts 2 and a top plate 3. Key levers 4 are fulcrumed on a fulcrum plate 5 in the rear of the base, each of said key levers

being provided with a restoring spring 6. Pivoted at 7 to each key lever is a sub-lever 8 which is slotted at its lower end portion to coöperate with a fixed abutment 9 supported 5 at the sides of the base. The upper end of each sub-lever is connected by a link 10 with a type bar 11, said type bar being pivotally mounted in a hanger 12 secured by a screw 13 to a segmental support 14. The hangers 10 are circularly arranged on the support and the free ends of the type bars 11 are normally supported on a type rest 15, said type bars when actuated coöperating with the front face of a rotary platen 16 mounted in a U-shaped platen carrier or carriage composed 15 of side or end bars 17 and a rear bar 18 connecting said side bars. The rear bar is provided at its top and bottom with oppositely disposed longitudinal grooves which coöperate 20 with anti-friction balls 19, said balls also coöperating with fixed grooved rails or trackways 20 secured by screws 21 to rearwardly bowed or curved standards 22 rising from the top end plate 3. Horizontally disposed and 25 rearwardly projecting arms 23 are pivoted in the side bars 17 of the carriage, said arms 23 supporting at their rear ends a carriage rack 24 which normally meshes with a feed pinion 25 secured to a shaft 26 journaled on a 30 bracket 27 rising from the top plate. A toothed escapement wheel 28 is operatively connected with the shaft 26, and coöperative with said escapement wheel are two escapement dogs 29 mounted at the top of a vibratory dog carrier or rocker 30 pivoted in a 35 supporting bracket 31 depending from the top plate. The dog rocker is provided with a horizontally disposed and forwardly projecting arm 30^a which is connected by a link 40 32 with a central rearwardly extending arm 33 of the universal bar frame, said frame comprising further a rock shaft 34 journaled at the sides of the base and a universal bar proper 35 extending from side to side of the machine beneath the series of key levers 4. 45 The universal bar is adapted to be operated when any of the key levers is actuated, thereby causing the dog rocker to be vibrated and the dogs 29 to coöperate in a known manner 50 with the escapement wheel 28 to permit the carriage to be drawn a letter space distance at a time leftward across the top plate under the influence of a spring drum 36 with which said carriage is connected by a band or strap 37. 55 Ribbon spools 38 (only one of which appears in the drawings) are arranged above the top plate, one on each side of the machine and forward of the platen. A ribbon 39 is wound upon the ribbon spools, said ribbon, 60 as herein shown, being divided longitudinally in fields *a* and *b* of different characteristics; that is to say, the field *a* or upper field may be one color such as black and the field *b*, or lower field, of a different color such as 65 red, or the field *a* may be copying ribbon and

the field *b* record ribbon for example. The ribbon 39 may be fed longitudinally from either spool to the other by any suitable means, that shown in the drawings being substantially the same as the ribbon feeding 70 mechanism employed in the Monarch typewriter. Each ribbon spool 39 is carried by an upright shaft 40 (Figs. 1 and 2) which rotates in a fixed bearing 41 and has secured to its lower end a small beveled gear 42. The 75 gear 42 meshes with a beveled pinion 43 secured at the forward end of a horizontal shaft 44 carrying at its rear end a beveled pinion 45, said pinion 45 being adapted to mesh with a beveled driving pinion 46 80 mounted on a driving or power shaft 47. Rotary movement is transmitted to the shaft 47 by beveled pinions 48 and 49, the pinion 48 being operatively connected with the driving shaft and the pinion 49 with the spring drum 85 36. It will be understood that both ribbon spools are provided with like gear trains which are adapted to be actuated by driving pinions 46 on the shaft 47. Said shaft is journaled in lugs 50 depending from the under side of the top plate and is capable of both longitudinal and rotary movements in its bearings, the longitudinal position of said shaft determining which driving pinion 46 will be in mesh with its coöperating pinion 45 and which ribbon spool will be turned to wind the ribbon thereon.

Midway between the ribbon spools the ribbon 39 is threaded through a vibratory ribbon carrier or vibrator 51, said vibrator 100 being guided and supported on a guide bracket 52 suitably secured to the top plate of the machine. The stem 53 of the ribbon carrier or vibrator has secured at its lower end a cross pin 54 which is engaged by the slotted forward end of an operating member or lever 55 fulcrumed at 56 in a lug 57 depending from the top plate. The free end of the forward arm of said lever is pivotally connected with the stem of the vibrator 51 and the rear arm is formed with a longitudinally extending slot 58. Engaging said slot is a pin 59 extending laterally from the upper end of a link 60, said link curving forward and downward from said pin 59 at the front side of the driving shaft 47 and then extending downward and being pivotally connected at its lower end to the arm 33 of the universal bar frame. A coiled spring 61 is connected with the link 60 and with the link 32 as 110 shown in Fig. 1, said spring tending to draw the link 60 rearward and to maintain the pin 59 at the rear end of the slot 58. The construction is such that when a key lever 4, or the space bar (not shown), is operated the 115 link 60 will be drawn downward and, through its pin and slot connection with the operating lever 55, will swing the rear arm of said lever downward and lift the forward arm thereof. The normal positioning of the vi- 120 130

brator is such that the ribbon is normally maintained below the printing point but when the operating lever is actuated the vibrator will be thrown upward to interpose the ribbon between the types on the actuated type bar and the front face of the platen.

When a ribbon like 39 having longitudinal fields or stripes of different characteristics or colors is employed in a machine having a vibratory ribbon carrier, it is necessary to vary the movement of the carrier in order to bring one field or another of the ribbon as desired opposite the printing point. In the present instance it is preferred to effect this result by providing a cam member adjustable to co-act with the link 60 to swing the latter back and forth on its bearing in the universal bar arm 33 and lengthwise of the operating lever, thus varying the position of the pin 59 in the slot 58; or in other words, varying the power arm of the operating lever. It is to be understood, however, that this is only one way of effecting the change or shift of the ribbon fields and that various other ways of accomplishing this result may be used within the invention. The cam member or ribbon field changer herein illustrated is designated as a whole by the numeral 62 and is in the nature of a sleeve which is mounted on the ribbon driving shaft 47. Said member comprises a cylindrical face 63 of comparatively narrow diameter, a cylindrical face 64 of large diameter, a coned or cam portion 65 joining said two faces and a hub portion 66, the latter being provided with a circumferential groove or depression 67. The member 62 is adapted to be slid lengthwise of the shaft 47 without affecting the latter and said shaft may also be moved endwise without affecting the member 62. If desired the member 62 may be connected with the shaft 47 by a pin and slot connection 68, 69, whereby the member 62 may be rotated by the driving shaft, but the faces 63, 64 of said member are concentric with the axis of the shaft 47 and it is not material whether the member 62 turns with the shaft 47 or not.

When the member 62 is positioned relatively to the link 60 as shown in Figs. 1, 2, 4 and 6, the cylindrical face 63 of said member will be in the path of said link and the spring 61 will operate on the link to swing or pull it rearward until said link contacts with the face 63, at which time the pin 59 will be at the rear end of the slot 58 and comparatively distant from the fulcrum 56 of the operating lever. An actuation of one of the key levers at this time will communicate to the ribbon carrier or vibrator its least throw or extent of upward movement, the parts being so proportioned and arranged that this throw will bring the upper field *a* of the ribbon opposite the printing point. This field *a* will be presented to the types at each actuation of a printing key as long as the member 62

remains in the position referred to. It will be apparent that by moving the member or ribbon field changer 62 longitudinally of the shaft 47 towards the right as viewed in Fig. 4, the coned portion 65 of the member 62 will coöperate with the rear edge of the link 60 and will cam or force said link forward against the tension or pull of the draw spring 61. If this movement of the member 62 be continued until the face 64 is brought into engagement with the link 60 and the member 62 be then arrested in the position shown in Fig. 5, it will be apparent that the pin 59 will be moved forward lengthwise of the slot 58 and will be arrested near the front of said slot. The dotted lines in Fig. 1 show the position of the link 60 and pin 59 at this time. It will further be apparent that the power arm of the operating lever has thus been shortened and that the extent of movement or throw of the vibrator has been correspondingly increased. The parts are so proportioned and arranged that if at this time a printing key be operated the ribbon carrier will be thrown or lifted upward far enough to bring the lower field *b* of the ribbon opposite the printing point in position to coöperate with the types. The particular means herein employed for accomplishing the object of the invention operates to shift the member 62 lengthwise of the driving shaft to bring one or another of the faces 63 or 64 into coöperation with the link 60, said means comprising devices on the frame of the machine which are automatically actuated by adjustable devices carried by the traveling element or carriage. The automatic shifting means on the frame comprises a forked arm 70, the lower or forked portion whereof extends into or engages the groove 67 in the member 62. The arm 70 is secured at its upper end to a short rod 71 which is slidably supported in one of the lugs 50 and in a smaller lug 72 depending from the top plate. The rod 71 has suitably secured to it three collars 73, 74 and 75. The collar 73 is adapted to co-act with the lug 72 to limit the movement of the rod 71 in one direction. The collar 75 is provided with an upwardly extending pin 76 which is connected with means for manually adjusting the rod 71, while the collar 74 is connected with automatic adjusting devices. In other words, the rod 71 and the forked arm 70 are adapted to be shifted to set the member 62 either manually or automatically and may be said to be comprised in both the manually operating and automatically operating means. These means are in a sense interdependent and before proceeding further with the detailed description of the automatically operating means, the manual means will be described, as said means coöperates with a stop device which normally positions the member 62 in the relation with the link 60 shown in Figs. 1, 2 and 4.

The manually controlled adjusting devices are best shown in Figs. 2 and 3 and comprise a bell crank lever 77 which is provided with a hub portion 78, the latter receiving a headed and shouldered screw 79 which screws into the top plate from the under side and serves as a pivot for the bell crank lever 77. One arm of said lever projects forward and is formed with a slot 80 which engages the pin 76. The other arm of said lever is pivotally connected at 81 to a link 82 which extends forward horizontally beneath the top plate and is pivotally connected at 83 with one arm of a bell crank lever 84, the latter being provided with a hub portion 85 which receives a headed and shouldered screw 86, the latter being secured in the under side of the top plate and serving as a pivot for the bell crank lever 84. One arm 84^a of the latter 15 extends forward through an opening 87 formed between the under side of the top plate and the upper edge of the front plate 88 of the machine and is provided at its forward end with a finger button 89. A stop device in the form of a lever 90 is pivoted at 20 91 to the front plate 88 and is provided at its free end with a finger piece 92 by which it may be swung up and down on its pivot. The stop lever 90 is provided with two stop 25 lugs 93 and 94 which extend upward from the top edge of the lever and are adapted to coöperate at their left-hand faces with the right-hand face or edge of the lever arm 84^a. As shown in Figs. 2 and 3 the stop lug 93. 30 is in coöperation with the lever arm 84^a, said lever arm being maintained against said stop lug by a coiled spring 95 which is connected at one end to a pin 96 extending horizontally forward from the rod 71 near its left-hand end, said spring at its other end being connected to a pin 97 extending horizontally forward from the lug 72. As will be apparent from a consideration of Fig. 2 the spring 95 tends to slide the rod 71 horizontally rightward in its bearings or away from the middle of the machine, and, through the pin and slot connection with the bell crank lever 77, to turn said lever on its pivot and move the link 82 longitudinally rearward. The link in 40 45 turn tends to swing the forward bell crank 84 on its pivot and will force the arm 84^a into contact with the stop lug 93 as shown. It will be noted that at this time the face 63 of the member 62 is coöperative with the link 50 55 60 so that the upper field *a* of the ribbon is operative. The manual adjustment or setting of the member 62 by means of the hand-controlled devices just described will be explained later in detail.

60 Returning now to the automatic shifting devices, the collar 74 is provided with a rearwardly extending horizontal pin or lug 97, which lug serves to connect the rod 71, arm 70 and member 62 with the shifting devices 65 on the frame of the machine. These de-

vices comprise a crank arm 98 provided at its lower end with an angled slot 99 which receives the pin or stud 97 and provided at its upper end with a collar portion through which passes the forward end of a horizontally disposed rock shaft 100. Said rock shaft is journaled in the depending arms 101 of a U-shaped bracket 102 which is secured by a headed screw 103 to the under side of the top plate. A crank arm 104 is provided with a collar portion through which the end of the rock shaft 100 passes, the crank arm 104 and the rock shaft being suitably secured in a fixed relation and said crank arm extending upward from the rock shaft through an opening or slot 105 in the top plate 3.

As will be understood from a consideration of Figs. 1 and 2, the rock shaft is prevented from moving endwise in its bearings by the collar portions of the crank arms 98 and 104, said collar portions abutting against the outer faces of the bracket arms 101. It will further be apparent that the crank arms and the rock shaft constitute in effect a single lever with an elongated fulcrum or pivot. 90 The crank arm 104 is formed at its upper end with two forks or branches which receive pins or studs 106 and 107. These studs, as shown in Figs. 1 and 4, are normally above the top plate and project towards the rear of the machine. Coöperative respectively with the studs 106 and 107 are forks or fingers 108 and 109 which constitute the lower arm of a two-armed lever, said lever further comprising a hub portion 110 and an upwardly 100 extending arm 111.

The hub portion is perforated to receive a headed shoulder screw 112 which passes through said collar portion, thence through an opening in a lever 113 (said lever being 105 comprised in a back spacing mechanism not herein shown) and then screwing into the lower fixed guide rail 20. The upper end of the lever arm 111 is pivotally connected by a headed pin or rivet 114 with one end of a floating bar 115, said bar extending lengthwise of the carriage bar 18 at the rear thereof and being pivotally connected at its other end by a headed pin or rivet 116 with an arm 117. The latter has a collar portion 118 115 which receives a headed shoulder screw 119 secured to the lower rail 20 and serving as a pivot for said arm 117. A wire spring 120 is coiled around the hub 118 and tends constantly to throw the arm 117 and the floating bar 115 and other parts connected therewith towards the right, as viewed from the rear of the machine. The floating bar 115 is guided by a slot-way 27^a in the bracket 27 and is arranged to have a parallel motion. Said floating bar is provided with a stepped portion 121 having a horizontal upper edge or face 122 and vertical side edges or faces 123 and 124. The edges or faces of the floating bar are adapted to coöperate with one or 120 125

more shifting or contact members or devices mounted on the traveling element or carriage. When the floating bar is moved from the normal position shown in Fig. 4 in the 5 direction of the arrow in Fig. 5 to the position shown in the latter figure, said floating bar operates through the finger 108 on the pin 106 to swing the lever on which said pin is mounted, the slot 99 in the lower arm of 10 said lever coöperating with the pin 97 to slide the rod 71 inward towards the middle of the machine and bring the face 64 of the member 62 into coöperation with the link 60, thereby effecting a change in the ribbon 15 field presented to the types when the printing keys are subsequently actuated. As has been stated, this operation of the floating bar to effect an automatic change in the ribbon fields is caused by the co-action with said 20 bar of a shifting member or members on the carriage or traveling element.

The field changing mechanism is preferably employed with tabulating mechanism. The tabulating mechanism shown in the 25 present case is substantially the same as that employed in the No. 3 Monarch typewriter and forming the subject-matter of the application of Jacob Felbel, Serial No. 270,527 filed July 20, 1905. Said tabulating mechanism comprises one or more tabulator stops commonly called column stops which are mounted on the carriage, and which coöperate with a plurality of tabulator stops, commonly called denominational stops mounted 30 a letter space distance apart on the frame of the machine. In the form of the invention now under consideration it is preferred to slightly modify one or more of said column stops and to make use of them as shifting 35 members to coöperate with the shifting member or floating bar 115 to effect an automatic change of ribbon fields. As is well understood the column stops presently to be described in detail are adjustable to assist 40 in defining columnar fields; and it will be apparent from what has been said that when one or another of the modified or special column stops is adjusted it not only assists to define a columnar field but also operates to 45 effect an automatic change of the ribbon fields so that the printing in the defined columnar field will be in a different color from the writing which has immediately preceded. Referring to Figs. 1 and 4, brackets 125 are 50 secured by headed screws 126 at the back of the rear bar 18 of the carriage near the ends thereof. Said brackets 125 are formed with rearwardly extending arms 127 which are perforated to receive the end portions of 55 a rectangular column stop bar 128 provided at its front and rear sides with oppositely disposed teeth 129. The end portions 130 of the column stop bar are cylindrical in shape, and are threaded to coöperate with 60 adjusting and securing nuts. The stop bar

128 is adapted to carry one or more adjustable flat column stops 131, said column stops being received in openings between the teeth 129 of the stop bar and each having a stopping portion 132 which is coöperative with 70 the denominational stops presently to be described.

In addition to the column stops 131 which are of the usual form, the stop bar 128 is adapted to support one or more special stop 75 members 133. Each of said members is made preferably of sheet metal and generally resembles the column stops 131, being adapted to fit down over the stop bar between the teeth thereof and having a stopping portion 134 coöperative with the denominational stops. Said stop members 133, however, differ from the regular column stops in that each is provided with a depending extension or shifting arm 135 which 80 extends some distance below the bottom face of the stop bar 128 into position to coöperate with the stepped portion 121 of the floating bar in a manner hereinafter described. It will be understood that the special members 90 each combine the functions of a tabulating stop and a shifting member, and that said members are each adjustable lengthwise both of the stop bar 128 and of the carriage on which said stop bar is supported. Said 95 special members may be arranged one following the other on the stop bar or may be combined in any desired way with the ordinary column stops as the work to be type-written may determine.

It will be apparent from an inspection of Fig. 1 that the curved standards 22 permit of the free and unobstructed passage of the stop bar 128 and the devices supported thereon as the carriage travels to and fro 105 across the top plate. During the travel of the carriage from left to right the column stops 131 and the members 133 are adapted to coöperate with a set of denominational stops, said stops being in the form of upright 110 levers 136 having forwardly curved stopping portions 137, said levers being pivoted between their ends at 138 in a supporting frame comprising side arms 139 joined at their tops by a part 140 which serves as a 115 hood for the upper ends of the levers 136, said frame being suitably secured to the frame of the machine at the rear thereof as by screws 141. Coiled springs 142 coöperate with the lower arms of the levers 136 to 120 maintain the stopping portions 137 normally out of the path of the column stops and the special members. Operative on the end portion of the lower arm of each lever 136 is a slide bar 143 mounted to slide on a frame 125 144 detachably secured to the main frame of the machine. Rock shafts 145 are journaled on the frame 144, each rock shaft having a depending arm 146 arranged to coöperate with the forward end of one of the slide bars 130

143. Each rock shaft has fixed to it also a horizontally disposed and forwardly extending lever arm 147 which is provided at its free end with a tabulating key 148. It will be understood that when a tabulating key is operated it turns its associated rock shaft and causes the arm 146 depending from said rock shaft to push the associate slide bar 143 rearward, said slide bar actuating the associate stop lever 136 and bringing the stopping portion 137 thereof into the path of the stopping portions of the column stops and the special members 133. In order to bring the co-operative tabulator stop members into engagement when the tabulating mechanism is operated, it is necessary to effect the release of the carriage from its step-by-step feeding mechanism. Said release is accomplished by means comprising a universal bar 149 arranged behind and transversely of the lower arm of the levers 136. Said universal bar has an arm 150 depending from it at each end and pivoted at 151 in the side bars 139 of the supporting frame, only one of said arms and pivots being shown in the present case. Projecting forward from the right-hand arm 150 is an extension 152 with which is pivotally connected at 153 the lower end of a vertically disposed link 154, said link being raised 25 when the universal bar 149 is actuated by one of the levers 136. The upper end of the link 154 is connected at 155 with a lever 156 pivoted at 157 on an arm 158 depending from the top plate. The inner arm of the lever 30 156 is pivotally connected at 159 with the lower end of a lifting member 160, the upper portion whereof is bifurcated to provide arms 161 which embrace or straddle the bracket 27. The upper end portions of the arms 161 35 are bent forward horizontally to provide lifting shoes 162 which normally lie beneath and out of contact with the teeth of the feed rack 25. When one of the tabulating keys is operated the link 154 is moved upward operating on the lifting member 160 through the lever 156, causing the lifting shoes 162 to engage the rack 25 and swing the latter upward on its pivots until it is disconnected from the feed pinion 26, thereby releasing the 40 carriage. The parts are so arranged that prior to the release of the carriage from its step-by-step feeding mechanism the actuated denominational stop lever will have been moved so that its stopping portion or denominational stop proper 137 will be in position to arrest the proximate column stop or that stop which is nearest to it at the right hand side looking from the front of the machine.

45 60 From what has been said it will be understood that the automatic operation of the ribbon field changing mechanism is effected at a predetermined point or points in the line of writing, the point or points being determined by the position at which the member

or members 133 are arranged on the stop bar 128. The arrangement of these members on the stop bar will, of course, depend on the character of the work to be written. The work, for example, may comprise a number 70 of columns of tabulated matter and one or more of these columns at the left-hand side of the work sheet may be in black, then there may be a column or columns to be written in red succeeded by a column or columns in 75 black. If the work sheet be ruled, a side guide (not shown) of suitable construction may be employed to properly position said work sheet when it is initially entered in the machine, and then the column stop or stops 80 131 and the combined column stops and shifting member or members 133 may be correspondingly adjusted by the aid of the usual platen scale (not shown) and the scale (not shown) with which the top face of the stop 85 bar 128 is preferably provided. For example, if the form printed and ruled on the work sheet shows that the first column is to be in black and to be begun at a point corresponding say to "24" on the platen scale, a column or tabulator stop 131 may be adjusted at a corresponding point on the tabulator stop bar. Assuming that the next succeeding column is to be written in red and begins at a point, say corresponding to "52" 90 on the platen scale, then one of the members 133 may be adjusted at a corresponding point on the stop bar 128. The next column may be in black, beginning at "62" and the next column after that may be in red beginning at "72". The adjustment of the stops and members just referred to is shown in Fig. 4, which it will be recalled is a rear view. Assuming that any preliminary writing on the work sheet has been written in the usual 105 way and that the carriage has been moved to the right ready to begin the tabular or column work, the operator presses the proper tabulating key 148 for arresting the carriage in the first column at the position to begin 110 the writing of the desired entry or number in that column. The depression of the tabulating key effects the release of the carriage and projects the corresponding denominational stop proper 137 into the path of the 115 tabulator stops on the stop bar. The carriage when released will move freely towards the left under the pull of the spring drum and will be arrested when the projected stop 137 is engaged by the first column stop or that stop adjusted at the point "24" on the stop bar. During the run of the carriage the first column stop will pass over the floating bar 115 without affecting either it or the field changing devices with which it is connected. 120 Consequently the member 62 will remain in normal position with the face 63 operative, and the writing in the first column will be in black. Let it be assumed that the writing in this first column has been completed and 130

that the parts are in the positions illustrated in Fig. 4, then the next entry will be in the column in part defined by the first of the members 133 which member was arranged at 5 the point "52" on the stop bar. The operator depresses the desired tabulator key 148, releasing the carriage and projecting the associate stop 137. The carriage when released will move freely towards the left, 10 bringing the shifting arm or extension 135 of the first member 133 against the face 123 of the floating bar. After contact of the extension with the face 123, further movement of the carriage swings the floating bar towards the right, as viewed from the rear of 15 the machine. The floating bar will first rise slightly because of the diagonal position of the arms 111 and 117 and will then, as its rightward longitudinal movement continues, 20 swing downward until it reaches the position shown in Fig. 5, from which it will be noted that the bar has during its movement towards the right been lowered far enough to enable the bottom of the extension 135 to 25 clear the face 123 and to ride over the upper face or edge 122 of the stepped portion 121. After this, during, the further run of the carriage the extension 135 will ride freely over the face 122 until the first member 133 30 contacts with the projected stop 137, whereupon the carriage will be arrested. During the movement of the extension over the face 122 the floating bar will be held in the depressed position shown in Fig. 5. From a 35 consideration of this figure it will be apparent that the relation between the set of tabulator stops or blades 137 and the stepped portion 121 of the floating bar is such that the floating bar reaches the end of its rightward movement just before the member 133 reaches the 40 stop 137 corresponding to the highest denomination. In other words, as the member 133 reaches the field of the tabulator stops 137, said member will begin to slide over 45 the face 122 of the stepped portion and will maintain the floating bar in depressed or operated position until said member 133 passes out of the field of the tabulator stop 137 at the right thereof, as viewed from the 50 rear. At all times, therefore, when co-operation is possible between the member 133 and one or another of the tabulator stops 137, said member is maintaining the floating bar 115 in operated position and the change 55 or shift of the ribbon fields will take place and remain only during the passage of the member 133 across the field of the stops 137. This last fact will perhaps be a little clearer after a word of explanation. The rightward 60 movement of the floating bar under the influence of the shifting member 133 acts through the train of devices with which said bar is connected to slide the rod 71 inward towards the middle of the machine, overcom- 65 ing the pull or tension of the spring 95 and

sliding the field changing member 62 lengthwise of the shaft 47 until the face 64 engages the link 60. This operates to swing the link forward about its lower end and brings the pin 59 at the upper end of said link nearer to 70 the fulcrum 56 of the operating lever 55. As long as the floating bar is held in the position shown in Fig. 5 the field changing member 62 will be maintained with its face 64 operative. The actuation of any of the printing keys at 75 this time will give the ribbon carrier its greatest extent of throw and will bring the lower field *b* of the ribbon opposite the printing point in position to co-act with the actuated type bar. Consequently no matter 80 which one of the stops 137 is projected to arrest the carriage by co-action with the first member 133 any printing in this column, which it will be recalled is the second column, will be in red. Let it be assumed that the 85 final digit in this second column has been printed and the extension 135 has just passed out of the field of the stops 137. Simultaneously with such passage the extension 135 clears the top face 122 of the floating bar, 90 thus permitting the spring 95 to operate on the member 62, the floating bar and the train of devices connecting these parts, restoring all of them to the normal position shown in Fig. 4. The link 60 is thereby permitted to be restored to normal position under the pull of its spring 61 and will again contact with the face 63 so that if a tabulator key be now operated to release the carriage and arrest it in a position in part determined 95 by the second column or tabulator stop 131, which stop was adjusted at the point "62" on the stop bar, then any printing in this column will be in black. After the entry has 100 been made in this column, which will be the third column, the appropriate tabulator key may be depressed to release the carriage and arrest it in the proper position in the fourth column, which fourth column is in part defined by the second shifting member 133. 105 During the run of the carriage from the third to the fourth column, the shifting member will co-act with the face 123 of the floating bar and will swing said bar rightward and downward far enough to enable the extension 135 to ride over the face 122, thus again 110 automatically changing the ribbon fields from black to red. 115

Assuming that the entries in the fourth column have been completed and that the extension 135 has cleared the face 122, permitting the floating bar, the field changing member and their associate parts to return to normal position, then the operator may line space the work sheet in the usual manner 120 and restore the carriage from left to right to begin a new line of writing. During this 125 restoring movement of the carriage the extension 135 will be brought against the vertical face 124 of the floating bar and will 130

swing said bar longitudinally in the direction of the arrow in Fig. 6, and downward until said bar reaches the position illustrated in said figure. It will be understood that this movement of the floating bar enables the extension 135 to ride over the face 121, thus permitting free rightward movement of the carriage to continue. After the extension 135 clears the face 121 the floating bar will be restored to normal position by its spring 120. It will be understood that during the to-and-fro movement just referred to of the floating bar, only said bar and the parts on which it is pivoted will be moved, and the field changer 62 and the train of devices connected therewith up to and including the arm 104 will remain quiescent. This is true because during this downward swing of the floating bar the fingers 108 and 109 will move away from their associate pins 106 and 107 and no movement will be communicated to the arm 104. The operation above described between the floating bar and the shifting member will be repeated when the other shifting member engages the floating bar. From what has been said it will be apparent that after the carriage reaches the initial position for the second line, the various parts will be in normal position and the second and subsequent lines of the entries may be written in the described manner.

Sometimes it may be desirable to print an entire line or succession of lines in printing of uniform characteristics, or, as in the present case, in a single color. To enable work of this sort to be done, the hand-controlled devices operated by the finger piece 89 may be employed in connection with the stop member or lever 90. Suppose it is desired to print an entire line or succession of lines in black. In that case the handle or finger piece 92 is pushed down from the full line position shown in Fig. 3 to that shown in dotted lines, thus withdrawing the stop lug 93 from the path of the lever arm 84^a and permitting the spring 95 to operate on the lever 84 and the train of devices connected therewith down to and including the member 62 with the result that said member 62 is slid along the shaft 47 in the direction of the arrow in Fig. 7 until said member attains the position shown in said figure. From a consideration of Fig. 7 it will be noted that the face 63 of the member 62 is still in coöperation with the link 60 so that the throw of the vibratory ribbon carrier will not be altered and it will present the ribbon field *a*, or black field, to the types when it is operated the same as it normally does. By the movement of the parts under the pull of the spring 95, however the rod 71 will be moved in the direction of the arrow in Fig. 7 until arrested by the co-action of the collar 74 with the lug 50. This movement of the rod 71 operates through the pin

97 on the lever arms 98 and 104 and will cause the pin 107 on the latter arm to co-act with the finger 109, swinging said finger rightward and the upper arm of the lever of which it is a part leftward and lowering the floating bar 115 to the position shown in Fig. 7. From this figure it will be noted that the face 122 of said bar has been brought down out of the path of the extension 135 of the shifting members 133. The result will be that during to-and-fro movements of the carriage the shifting members thereon will not contact with the shifting member or floating bar on the frame, so that the carriage movements may be uninterrupted and the face 63 of the ribbon field changer may remain operative, with the result that all the writing will be in black.

If it be desired to do all the writing from the red or lower ribbon field *b*, the handle or finger piece 89 may be pressed leftward, overcoming the pull of the spring 95 and forcing the rod 71 and the ribbon field changer 62 towards the right as viewed in Fig. 5 until the collar 73 contacts with the lug 72, thus arresting the parts, the face 64 at this time being coöperative with the link 60. This rightward movement of the rod 71 causes the pin 107 to swing towards the left and during this leftward movement of said pin it will be followed up by the finger 109 under the influence of the spring 120. Consequently when the rod 71 is arrested by the lug 72, the floating bar 115 will have been swung towards the right and downward far enough to enable the extensions 135 to just clear the upper face 122 of said floating bar. The parts may be maintained set in the positions just referred to by swinging the stop member 90 upward and bringing the stop lug 94 to the right of the lever arm 84^a as viewed from the front of the machine, so that the left-hand vertical face of the lug 94 will prevent rightward movement of said arm 84^a under the pull of the spring 95. 110

When it may be again desired to render the automatic shifting devices operative, this may be accomplished by pulling down the stop member 90 until the lug 94 is out of the path of the lever arm 84^a, thus permitting said arm to move rightward under the pull of the spring 95 and to again co-act with the stop lug 93. 115

If one or more of the red columns are of greater width than the distance between the first and last denominational stops, it is only necessary to adjust two or more stop members on the stop bar in such a way that before the first member reaches the end of the stepped section of the floating bar another member will engage said section and maintain the floating bar depressed. 120

It may sometimes be desired to make an entry, say in black, within a column already set off for red records; in which case the black 13

entry may be made without shifting the bell crank 84 by hand, as follows:—The operator depresses the tabulator key of lowest denomination, thus projecting the corresponding 5 denominational stop which will be the right-hand stop as viewed from the rear of the machine and causing the carriage to be arrested with the appropriate member 133 in contact with said projected stop. After the carriage 10 has been thus arrested the space key may be depressed to move the carriage an additional letter space distance, thus releasing the floating bar and permitting the parts to return to normal position. Thereupon the carriage 15 may be moved in return direction by hand to the desired denominational position, during which carriage movement the member 133 will operate to lower the floating bar but will not effect the field changer 62. Consequently 20 if the printing keys be now operated the printing will be done in black.

Various changes may be made without departing from the spirit and scope of my invention.

25 What I claim as new and desire to secure by Letters Patent, is:—

1. In a typewriting machine, the combination of a carriage, printing instrumentalities, ribbon fields of different characteristics normally removed from the printing point, devices for moving said ribbon fields to and from the printing point at printing operation, and means operative at a predetermined point in the carriage travel to alter the normal relation between certain of said devices. 30 35 40 45

2. In a typewriting machine, the combination of a carriage, printing instrumentalities, ribbon fields of different characteristics, a ribbon vibrator normally maintaining said ribbon fields away from the printing point, devices operative to move said vibrator to and from the printing point, and means operative at a predetermined point in the travel of the carriage to alter the normal relation between certain of said devices.

50 55 60 65

3. In a typewriting machine, the combination of a ribbon vibrator, devices operative to move said vibrator to and from the printing point, a member adjustable to vary the normal relation between certain of said devices, and means operating automatically to re-adjust said member at a predetermined point in the travel of the carriage.

4. In a typewriting machine, the combination of a ribbon vibrator, devices operative to move said vibrator to and from the printing point, a member adjustable to vary the normal relation between certain of said devices, a spring normally controlling the position of said member, and means automatically acting to overcome the force of said spring and re-adjust said member to change again the normal relation between certain of said devices.

65 70 75 80 85 90 95 100 105 110 115 120 125 130

5. In a typewriting machine, the combina-

tion of a carriage, printing instrumentalities, ribbon fields of different characteristics normally removed from the printing point, actuating devices for said ribbon fields including a link and a lever, and means operative at a predetermined point in the travel of the carriage to vary the normal relation between said link and said lever.

6. In a typewriting machine, the combination of a carriage, printing instrumentalities, a ribbon vibrator, actuating devices therefor including a link and a lever, and means operative at a predetermined point in the carriage travel to vary the normal relation between said link and said lever.

7. In a typewriting machine, the combination of a carriage, printing instrumentalities, a ribbon vibrator, an operating lever therefor, a key actuated universal bar, a link connecting said universal bar with said operating lever, and means for varying the normal relation between said link and said lever, said means operating at a predetermined point in the travel of the carriage.

8. In a typewriting machine, the combination of a carriage, printing instrumentalities, a ribbon vibrator, an operating lever therefor, a key actuated universal bar frame, a link pivotally connected with said universal bar frame and having a pin and slot connection with said operating lever, a spring tending constantly to maintain said link and operating lever in a normal relation, and means operative at a predetermined point in the travel of the carriage to vary the normal relation between said link and said operating lever.

9. In a typewriting machine, the combination of a ribbon vibrator, actuating devices therefor including a link and a lever, a member operative to vary the normal relation between said link and said lever, and means for readjusting said member, said means being operative at a predetermined point in the carriage travel.

10. In a typewriting machine, the combination of a ribbon vibrator, actuating devices therefor including a link and a lever, a member operative to vary the normal relation between said link and said lever, and means for re-adjusting said member, said means being operative at a predetermined point in the carriage travel and said means being adapted to be set to vary the point in the carriage travel at which said member will be re-adjusted.

11. In a typewriting machine, the combination of a carriage, a ribbon vibrator, actuating devices therefor including a link and a lever, a member operative to vary the normal relation between said link and said lever, and shifting members one operatively connected with the carriage and one on a fixed part, said shifting members co-operating at a predetermined point in the travel of the carriage.

carriage to re-adjust said first recited member.

12. In a typewriting machine, the combination of a carriage, a ribbon vibrator, actuating devices therefor including a link and a lever, a member operative to vary the normal relation between said link and said lever, and shifting members one operatively connected with the carriage and one on a fixed part, said shifting members coöperating at a predetermined point in the travel of the carriage to re-adjust said first recited member, one of said shifting members being adjustable relatively to the other to vary said predetermined point.

13. In a typewriting machine, the combination of a carriage, a ribbon vibrator, actuating means therefor including a link and a lever, a member adjustable transversely of said link and having a plurality of faces co-operative with said link to vary its relation with said lever, a shifting member mounted on a fixed part and operative to shift said adjustable member, and a second shifting member on the carriage operative on the first named shifting member.

14. In a typewriting machine, the combination of a ribbon vibrator, actuating means therefor including a link and a lever, a member having a plurality of faces, and means for automatically shifting said member at a predetermined point in the line of writing to bring one or another of said faces into position to coöperate with said link to determine its normal relation with said lever.

15. In a typewriting machine, the combination of a ribbon vibrator, actuating means therefor including a link and a lever, a member having a plurality of faces, means for automatically shifting said member at a predetermined point in the line of writing to bring one or another of said faces into position to coöperate with said link to determine its normal relation with said lever, and means for manually shifting said member.

16. In a typewriting machine, the combination of a ribbon vibrator, devices for moving said vibrator to and from the printing point, means operating automatically at a predetermined point in the line of writing to vary the normal relation between certain of said devices, said last named means being constructed and arranged to be rendered inoperative for the purpose of changing the ribbon fields.

17. In a typewriting machine, the combination of a ribbon vibrator, devices for moving said vibrator to and from the printing point, means operating automatically at a predetermined point in the line of writing to vary the normal relation between certain of said devices, said last named means being constructed and arranged to be rendered inoperative for the purpose of changing the

ribbon fields, and means for manually operating said first named means.

18. In a typewriting machine, the combination of a carriage, a ribbon vibrator, devices for moving said vibrator to and from the printing point, a member operative to vary the normal relation between certain of said devices to vary the throw of the vibrator, and means operative at a predetermined point in the travel of the carriage to vary the position of said member, said means including a shifting member operatively connected with the carriage and a shifting member mounted on the frame of the machine, the latter member being a bar having a parallel motion.

19. In a typewriting machine, the combination of a carriage, a ribbon vibrator, devices for moving said vibrator to and from the printing point, a member operative to vary the normal relation between certain of said devices to vary the throw of the vibrator, means operative at a predetermined point in the travel of the carriage to vary the position of said member, said means including a shifting member operatively connected with the carriage, a floating bar mounted on the frame of the machine and adapted to be given parallel movement by said shifting member, a cam member, and connections between said floating bar and said cam member.

20. In a typewriting machine, the combination of a carriage, a ribbon vibrator, devices for moving said vibrator to and from the printing point, a member operative to vary the normal relation between certain of said devices to vary the throw of the vibrator, means operative at a predetermined point in the travel of the carriage to vary the position of said member, said means including a shifting member operatively connected with the carriage, a floating bar mounted on the frame of the machine and adapted to be given parallel movement by said shifting member, a cam member, and connections between said floating bar and said cam member.

21. In a typewriting machine, the combination with a carriage, step-by-step feeding mechanism therefor, ribbon fields of different characteristics, a ribbon vibrator, devices for moving said vibrator to and from the printing point, and tabulating mechanism including stops operative to arrest the carriage in predetermined columnar positions, of a member coöperative with certain of said devices to alter their normal relations, and means operative during the movement of the carriage to a predetermined columnar position to shift or re-adjust said member.

22. In a typewriting machine, the combination with a carriage, step-by-step feeding mechanism therefor, ribbon fields of different characteristics, a ribbon vibrator, devices for moving said vibrator to and from the printing point, and tabulating mechanism including stops operative to arrest the carriage in predetermined columnar positions, of a member 5 cooperative with certain of said devices to alter their normal relations, and means operative during the movement of the carriage to a predetermined columnar position to shift or re-adjust said member, said means including certain of the 10 tabulator stops.
23. In a typewriting machine, the combination with a carriage, step-by-step feeding mechanism therefor, ribbon fields of different characteristics, a ribbon vibrator, devices for moving said vibrator to and from the printing point, and tabulating mechanism including stops operative to arrest the carriage in predetermined columnar positions, of a member 15 cooperative with certain of said devices to vary the normal relation between said devices, and means operated during the movement of the carriage to a predetermined columnar position to shift or re-adjust said member to render one or another of its faces 20 operative.
24. In a typewriting machine, the combination with a carriage, step-by-step feeding mechanism therefor, ribbon fields of different characteristics, a ribbon vibrator, devices for moving said vibrator to and from the printing point, and tabulating mechanism including stops operative to arrest the carriage in predetermined columnar positions, of a member 25 having a plurality of faces cooperative with certain of said devices to vary their normal relation, and a shifting member cooperative with certain of said tabulating stops to shift or move said cam member to bring different faces thereof into position to 30 cooperate with certain of said devices.
25. In a typewriting machine, the combination with a carriage, step-by-step feeding mechanism therefor, ribbon fields of different characteristics, a ribbon vibrator, actuating devices therefor including a link and a lever, and tabulating mechanism including stops operative to arrest the carriage in predetermined columnar positions, of a member 35 cooperative with said link, and means operative during the movement of the carriage to a predetermined columnar position to shift or re-adjust said member to render one or another of its faces 40 operative, said means including certain of the tabulator stops.
26. In a typewriting machine, the combination with a carriage, step-by-step feeding mechanism therefor, ribbon fields of different characteristics, a ribbon vibrator, actuating devices therefor including a link and a lever, and tabulating mechanism including stops operative to arrest the carriage in predetermined columnar positions, of a member 45 cooperative with said link, and means operative during the movement of the carriage to a predetermined columnar position to shift or re-adjust said member and vary the normal position of said link.
27. In a typewriting machine, the combination with a carriage, step-by-step feeding mechanism therefor, ribbon fields of different characteristics, a ribbon vibrator, actuating devices therefor including a link and a lever, and tabulating mechanism including stops operative to arrest the carriage in predetermined columnar positions, of a member 50 cooperative with said link, and means operative during the movement of the carriage to a predetermined columnar position to shift or re-adjust said member and vary the normal position of said link, said means including certain of said tabulating stops.
28. In a typewriting machine, the combination with a carriage, step-by-step feeding mechanism therefor, ribbon fields of different characteristics, a ribbon vibrator, devices for moving the vibrator to and from the printing point, and tabulating mechanism including 55 stops operative to arrest the carriage in prearranged columnar positions, of a cam member having a plurality of faces cooperative with certain of said devices to vary their normal relation, and a shifting member cooperative with certain of said tabulating stops to shift or move said cam member to bring different faces thereof into position to 60 cooperate with certain of said devices.
29. In a typewriting machine, the combination with a carriage, step-by-step feeding mechanism therefor, ribbon fields of different characteristics, a ribbon vibrator, devices for moving the vibrator to and from the printing point, and tabulating mechanism including 65 stops operative to arrest the carriage in prearranged columnar positions, of a cam member having a plurality of faces cooperative with certain of said devices to vary their normal relation, means for shifting said cam 70 member comprising a forked arm and a slide rod, and means for actuating said slide rod including a shifting member mounted on a fixed part and cooperative with certain of said tabulating stops to effect an actuation 75 of said slide rod during the run of the carriage to a predetermined columnar position.
30. In a typewriting machine, the combination with a carriage, step-by-step feeding mechanism therefor, ribbon fields of different 80 characteristics, a ribbon vibrator, devices for moving the vibrator to and from the printing point, and tabulating mechanism including stops operative to arrest the carriage in prearranged columnar positions, of means 85

operating automatically to change the ribbon field coöperative with the printing instrumentalities, said means comprising a floating bar mounted on the frame and co-acting 5 directly with one or more of the tabulator stops on the carriage, said means further comprising a cam member connected with said floating bar and coöperative with certain of said vibrator-moving devices to alter the 10 normal relation thereof.

31. In a typewriting machine, the combination with a carriage, tabulating stop mechanism including tabulator stop members on the carriage and tabulator stops on the frame 15 of the machine, of ribbon field changing mechanism including a field changing member, and a spring controlled floating bar connected therewith and contactive with a tabulator stop member on the carriage which 20 operates to actuate said bar and shift said field changing member, said field changing member being reshifted by its spring when the contact between said tabulator stop member and said floating bar ceases.

32. In a typewriting machine, the combination with a carriage, and tabulating mechanism including tabulator stop members on the carriage and tabulator stops on the frame of the machine, of ribbon-field-changing 30 mechanism including a field changing member, a spring-controlled bar having a stepped portion, said bar being connected with said member and its stepped portion being contactive with a tabulator stop member 35 on the carriage which operates against one face of said stepped portion to shift said bar and against another face of said stepped portion to maintain said bar shifted.

33. In a typewriting machine, the combination with a carriage, and tabulating mechanism including tabulator stops on the frame and tabulator stops on said carriage, of ribbon field changing mechanism including a field changing member, a spring controlled bar having a parallel motion and connected 40 with said member, said bar being contactive with and operative by a tabulator stop on the carriage, and hand controlled means for shifting said floating bar in two directions to change ribbon fields and render said tabulator stop members inoperative on said bar. 45

34. In a typewriting machine, the combination of a carriage and tabulating mechanism including a tabulator stop member on the carriage and a set of denominational stops 55 arranged side by side on the frame of the machine, of ribbon field changing mechanism including a spring controlled floating bar contactive with and movable by said tabulator stop member, said bar being maintained 60 in abnormal position by said tabulator stop member only during the passage of said member across the field of said denominational stops, said bar returning automatically to normal position when said stop member separates from said bar and simultaneously passes out of the field of said denominational stops. 65

Signed at Syracuse, in the county of Onondaga and State of New York this 13th day of December, A. D. 1907. 70
